Application June 12, 1940, Serial No. 340,060

6 Claims. (Cl. 159—49)

This invention relates to methods for drying liquors to form substantially dry solid products recoverable from such liquors by heating of the same to eliminate vaporizable constituents. For illustrative purposes, principles of the invention may be discussed in connection with the drying of disodium phosphate liquor to form substantially anhydrous disodium phosphate.

Anhydrous disodium phosphate is usually made by concentrating and dehydrating, in some way or other, a disodium phosphate liquor containing disodium phosphate in solution and in suspension. In modern practice, drum driers are used economically to eliminate water from any kinds of slurries and liquors. One conventional type of drier comprises a rotatable horizontally mounted metallic drum equipped with suitable steam pipe and valve connections to provide for internal steam heating. Adjacent the lowermost periphery of the drum is a trough placed lengthwise of the drum and into which is run whatever liquor is to be dried. Relation of drum and trough are such that on drum rotation a portion of the drum surface becomes immersed in the liquor in the trough, and on emergence from the bath certain quantities of liquor adhere to the outer drum surface. The apparatus includes a longitudinal stripping knife arranged to contact a portion of the drying surface at a point just prior to resubmergence of such portion in the liquor bath. In this way, dried material is shaved off the drier by action of the knife.

It has not been possible to secure consistent commercially satisfactory results by drying run-of-plant disodium phosphate liquors by customary operation of drum driers. In the case of many liquors, dried product adheres tenaciously to the metal surface of the drum making necessary the application of excessive pressure to the knife in order to scrape off dried product. Even heavy knife pressure is ineffective, and in many situations substantial quantities of material still adhere to the drum after passing the knife, indications being that some portions of the disodium phosphate become in a sense semi-fused to the metallic drum surface. Heavy knife pressure requires use of a large amount of power to turn the drier, and also results in rapid wearing away of the knife edge with necessity for frequent shut-downs for resharpening, realignment, or replacement. The disadvantages give rise to high power costs and low production per unit drier. Further, the substantially anhydrous product obtained is in an unsatisfactory powder-like form.

I have found that difficulties such as those enumerated, arising in the drying of run-of-plant liquors, may be overcome by forming on the heating surface of the drying equipment what, for descriptive purposes, may be considered as a double layer of the material to be dried. More particularly, I have discovered that the sought-for objects of the invention may be attained by forming on a heated drying surface an initial relatively thin layer of the liquor to be dried, heating the layer to convert the same to an at least partially dried crust, forming on such crust a second relatively thin layer of such liquor, and then continuing heating of the composite material on the said drying surface to form substantially dry solid material. I find that, as a result of practice of the procedure herein described, there is formed on the drying surface a relatively thick crust which, I believe from observations, resists tendency to rupture just sufficiently so that when the material becomes substantially dry and vapor pressure at the drying surface becomes sufficient, the crust cracks, rises, and breaks away cleanly from the drying surface. This action takes place to such an extent that the stripping knife acts more or less as a guide to direct the dried material into the collecting trough or bin.

As applied to the drying of disodium phosphate liquors, the invention may be understood from the following description taken in connection with the accompanying drawing, in which—

Fig. 1 shows diagrammatically the apparatus used;

Fig. 2 is a plan view of a supplemental feed trough;

Fig. 3 is an elevation of the trough taken on the line 3—3 of Fig. 2;

Fig. 4 is a vertical transverse section taken on the line 4—4 of Fig. 2; and

Fig. 5 is a fragmental horizontal section taken on line 5—5 of Fig. 3.

In Fig. 1, 10 designates a transverse vertical section of a horizontally disposed metallic drum rotatable about axis 11 and equipped with suitable steam pipe valve connections, not shown, to provide for internal steam heating. Beneath the drum is a primary, longitudinally disposed feed trough 12 into which is run, thru a valve-controlled pipe 14, the liquor to be dried from a suitable supply reservoir 16 equipped with adequate heating coils to keep the liquor to be dried at the desired working temperature. An agitator 17 may be used to prevent undue settling in trough 12. Arrangement of trough 12 and drum

10 is such that on rotation of the drum, a portion of the drum surface becomes immersed in the liquor in the trough, and on emergence from the bath certain quantities of liquor adhere to the outer drum surface in the form of a relatively thin layer. A longitudinal stripping knife 20 is positioned to contact the drying surface at a point just ahead of resubmergence of the drum surface in the liquor bath in trough 12, drum rotation being in the direction of arrow 21. Dried 10 material is directed by the flat surface of the knife into an elongated collecting bin 23. Liquor overflow from trough 12 runs thru pipe 25 into a sump 26, communicating by pipe 27 with the inlet side of pump 30 which returns from sump 18 26 thru pipe 31 to the reservoir 16. The apparatus as so far described may be considered conventional.

Practice of the present invention involves use of a secondary or supplemental feed trough 33 20 of length corresponding with the length of the drum drying surface. This trough is mounted, by suitable supports not shown, in a position immediately adjacent the drying surface and preferably slightly above the axis of rotation 28 of the drum, all as indicated in Fig. 1. The supplemental trough is shown in detail in Figs. 2-5.

Trough 33 comprises channel iron 35 to the opposite ends of which are attached rods 37 affording means thru which the trough, by supporting framework not shown, may be held in position against the drum surface. As will appear from Fig. 4, the flat surface 39 of channel bar 35 forms the back side of the trough channel. Attached to the channel bar at the lower horizontal edge of flat face 39 is a longitudinal triangular bar 42, to the sloping face of which is bolted a spring steel plate 44 extending the length of the trough. Resting on the horizontal face of bar 42 and also on the upper portion of plate 44 is a sheet 45 of relatively heavy canvas or other suitable flexible material securely held in place by a longitudinal metallic plate 48 and associated bolts 50 which pass thru the canvas and are threaded into bar 42. The width of the canvas is such as to afford a lip 51 flexibly contacting with any material on the immediately adjacent face of drum 10, and the length of the canvas strip corresponds with the length of the trough.

As shown in Figs. 2 and 3, L-shaped end plate 54 is bolted rigidly to channel face 39 as at 55. A movable rubber gasket 57, shown in plan in Figs. 2 and 5 and partly in elevation in Fig. 3, is sandwiched between the inner face of fixed end plate 54 and a movable supporting plate 59 on which are fixed studs 61 projecting thru the rubber gasket and into longitudinal slots 62 of end plate 54. The turned-in edge 66 of the rubber gasket is attached as at 68 in liquid-tight relation to the adjacent vertical edge of canvas strip 45. As shown in Fig. 3, the turned-in end of the gasket and the corresponding edge of inner supporting plate 59 are arcuate, conforming with the curvature of the drum. By loosening and tightening wing-nuts 70 on studs 61, gasket 57 and inner supporting plate 59 are movable as a unit toward or away from the drying drum.

Feed of liquor to trough 33 is effected by means of pump 30, pipe 31, and pipe 75 containing a control valve 76. Constant working level in the trough is maintained by overflow pipe 78 emptying into sump 26. Valve-controlled pipe 80 provides a by-pass around trough 33. By means of

5 pump 30 and the indicated relation of supply tank 16, both troughs and the associated pipe connections, it is possible to conveniently keep up a rapid circulation of a relatively large volume of liquor, regardless of rate of liquor drying, thus preventing possible clogging of the conduits and so-called "freezing" of the liquor.

When applying the principles of the invention to the drying of disodium phosphate, the liquors used may be produced in any suitable way. For example, the disodium phosphate liquor to be dehydrated may be made by melting the dodecahydrate in its own water of crystallization, and then concentrating the melt by heating. In large-scale operation, a suitable liquor to be dehydrated may also be the disodium phosphate liquor resulting from filtration, and subsequent concentration if necessary, of the liquor formed in the usual process for making hydrated disodium phosphate.

Especially when dehydrating disodium phosphate liquor by means of drying equipment such as a drum drier or similar apparatus where the drying surface passes thru and picks up an adhering layer of the liquor to be dried, it is advantageous to take into consideration the matter of concentration of the liquor used. It is preferred to carry out make-up of the disodium phosphate prior to drying so that the liquor fed into the drum drier supply troughs has a concentration of not less than 49° Bé. at temperatures in the range of 200 to 220° F. To facilitate formation, on the drum or other drying surface, of liquor layers of the more satisfactory physical characteristics, it is preferred to operate so that the concentration of the liquor in the feed troughs is not in excess of 51° Bé. at temperature of 200-220° F. Formation of such liquors may be effected by suitable control of the previously mentioned concentrating operation. Temperature of the liquor in the feed troughs and as actually fed onto the drying surface may vary considerably and is for the most part a matter of operating convenience, i. e. such temperature should be high enough to maintain the mass in the system in readily flowable condition.

Furthermore, when using the invention for drying of disodium phosphate liquors, instead of using any run-of-plant liquor, to obtain most advantageous results, i. e. high production per unit drier, it is preferred to feed to the drying surface a disodium phosphate liquor containing, by weight of the liquor, not more than 0.02% monosodium phosphate and not more than 0.05% trisodium phosphate, calculated on a 50° Bé. at 212° F. basis.

In instances where it is desirable to treat or adjust the liquor to be dehydrated to form a mass of the composition indicated, such treatment may be effected at any time during make-up. However, the more practicable procedure is to first bring the liquor, ordinarily by boiling weak liquor, to a concentration of about 50° Bé. at 212° F., determine the monosodium or trisodium phosphate content by known tests, and then calculating the amount of treating material needed to bring the liquor within the indicated monosodium-trisodium phosphate range. Adjustment may be accomplished by adding to the liquor sodium hydroxide or sodium carbonate on the one hand, or by addition of phosphoric acid on the other. Where the monosodium phosphate content exceeds 0.02% by weight on a 50° Bé. at 212° F. basis, requisite quanti-

ties of sodium hydroxide or sodium carbonate may be added to reduce the monosodium phosphate content to not more than 0.02% on the same basis. In this situation it is preferred to employ sodium carbonate since even though an excess of sodium carbonate were used, practically no trisodium phosphate would be formed, and hence there is no danger of forming a liquor containing more than 0.05% trisodium phosphate. In cases where the composition of the liquor is such that the trisodium phosphate content exceeds 0.05% on a 50° Bé. at 212° F. basis, the liquor is treated with a sufficient amount of preferably relatively pure phosphoric acid to reduce the trisodium phosphate content to not more than 0.05% on the same basis. Should the liquor to be dried have concentration of say 49° Bé. at 212° F. (instead of 50° Bé. at 212° F. as above indicated), determination of monosodium or trisodium phosphate content may be made as before. Conversion of such analysis to 50° Bé. basis may be had by multiplying such analysis by 50/49, and according to the value thus obtained the amount of treating material to be used may be calculated.

In practice of the invention, reservoir 16 is filled with liquor to be dehydrated and by suitable control of heating coils in the reservoir the liquor is kept at whatever temperature is desirable to facilitate flow of liquor thru the system. In drying disodium phosphate, it will be understood the liquor introduced into tank 16 is, in accordance with the best embodiments of the invention, preferably of a concentration and composition previously noted. Pump 30 is put in operation and circulation of the liquor is started thru troughs 12 and 33 and the associated pipe connections indicated in Fig. 1. It will be understood that in normal operation both troughs are kept filled to overflowing and there is a continual movement of liquor thru the troughs and connecting circulating pipes regardless of the rate of drying on the drum. Overflow of trough 12 is fixed so that the lower portion of the drying drum is immersed to an appreciable extent in the liquor. Feed to and overflow from trough 33 are adjusted so that there is a continual flow of liquor over lip 51 of trough 33 to such an extent that the material already on the drum surface, as the latter passes lip 51, becomes as thoroughly wetted as feasible with liquor from trough 33 without permitting any material runoff of liquor down the side of the drum. In this way it will be understood that by reason of the relationship of the drum and trough 12, there is first formed on the drum a layer of liquor to be dried. During movement of a portion of the drum surface from trough 12 up to lip 51 the material on such portion becomes at least partially and in most instances quite thoroughly dried. Such given portion of the drum passes under lip 51 and on account of the previously-mentioned liquor flow over lip 51, there is formed on the partially dried material already on the drum a second layer of the liquor to be dried. On further rotation of the drum heating of material on the drying surface continues, steam supply to the interior of the drum being such that all of the material on the drum surface has dried to the desired degree by the time a given portion of the drum reaches stripping knife 20.

Prior to development of the invention it was found that when using a run-of-plant disodium phosphate liquor containing for example 0.07% monosodium phosphate, from commercial view-

point the results obtained with respect to power consumption, dried product removal, physical form of the product, and knife readjustments and replacements were unsatisfactory and use 5 of a drum drier equipped with conventional single trough feed, e. g. trough 12, was entirely impracticable. Further, experience shows dried material removal from the drying surface became difficult and unsatisfactory where the trisodium 10 phosphate content exceeded the indicated 0.05% by weight. It was then found that by proceeding 15 as already indicated by forming on the heated drying surface a layer of liquor, heating the layer to convert the same to an at least partially dried crust, then forming on the crust a layer of the liquor and continuing heating the material on the drying surface to substantially dry the same, remarkably satisfactory results might be obtained even though, in the case of disodium phosphate liquors, the monosodium or disodium phosphate content might be outside the above indicated preferred operating range.

In one operation employing the double feed 20 of the invention, and using the same drum drier, the same steam pressure, and the same run-of-plant liquor containing 0.07% monosodium phosphate, production of 1320 pounds per hour of disodium phosphate having about 0.5% moisture content was obtained. In this procedure the 25 liquor in troughs 12 and 33 was at concentration of about 49.5° Bé., temperature of the liquor was about 211° F., average horse-power needed was 9, and R. P. M. of the drum was 2.6. In another 30 similar run, using double feed, the same drum drier, the same steam pressure, but a run-of-plant liquor which has been treated with sodium carbonate to form a mass containing 0.02% monosodium phosphate, an hourly production of 1680 pounds of substantially dry disodium 35 phosphate was obtained. In this case average R. P. M. of the drum was 2.6, average horse-power needed was slightly less than 8, concentration of the liquor was about 49.7° Bé., and temperature averaged 210° F. In both of these operations, using the run-of-plant liquor and the sodium carbonate treated liquor, most of the composite crust formed on the drum cracked and chipped off of its own accord prior to reaching the stripping knife, and only very moderate pressure on the stripping knife was necessary 40 to completely clean the drum.

In another set of parallel tests employing 45 run-of-plant disodium phosphate liquor, a drum drier about 14 feet long and about 5 feet in diameter, steam pressure at 56 pounds per square inch, average drum speed of 4.25 R. P. M. and operating with single trough (trough 12) feed alone, production was about 12 tons of substantially dry disodium phosphate per 24 hours. Using the same liquor and the same drum 50 equipped for the double layer feeding of the invention production was about 18 tons per 24 hours and drum speed was only 2.5 R. P. M.

No satisfactory explanation for the improved 55 results afforded by the invention has been developed. It has been observed, however, that when operating the drum with a single layer coating, the thickness of product particles is only 0.003-0.007 of an inch, whereas thickness of flaked product of the double coating procedure of the invention is generally 0.018-0.23 of an inch. It is thought that, since the initial coating is usually almost dry by the time the second layer is applied, the first coating provides a rough surface which holds much more

solution than is retained by the first application, and the result is formation of a composite crust from three to six times as thick as is obtained by single-layer application. Hence, it is possible, that the substantial increase in thickness of coating secured when double feeding is used affords a deposit which resists rupture tendency sufficiently so that when the material is substantially dry the vapor pressure on the surface of the drum and beneath becomes sufficient to crack 10 and raise the crust away from the drying surface in relatively large flakes or sheets.

The double layer feed method of the invention may be used to dry other liquors such as trisodium phosphate, sodium sulfate, calcium 15 acetate, calcium chloride, magnesium chloride, and sodium benzene sulfonate. Further, the invention may be practiced in connection with use of equipment other than a drum drier. For example, a heated metal belt drier, or a rotating 20 disk drier, or any other type of drier ordinarily including a knife for removal of dried material from the heating surface may be employed instead of a drum drier.

I claim:

1. In the process for drying disodium phosphate liquor by procedure involving use of a drum drier, the steps comprising forming on the drying surface of the drum a layer of disodium phosphate liquor, heating said layer to convert the same to an at least partially dried crust, forming on such crust a layer of disodium phosphate liquor, and continuing heating of the disodium phosphate material on the drum drying surface to thereby form substantially dry 35 material readily removable from said surface.

2. In the process for drying disodium phosphate liquor by procedure involving use of a drum drier, the steps comprising forming on the drying surface of the drum a layer of disodium 40 phosphate liquor of concentration of not less than 49° Bé. at temperature of 200-220° F., heating said layer to convert the same to an at least partially dried crust, forming on such crust a layer of said disodium phosphate liquor, and continuing heating of the disodium phosphate material on the drum drying surface to thereby form substantially dry material readily removable from said surface.

3. In the process for drying disodium phosphate liquor by procedure involving use of a drum drier, the steps comprising forming on the 45 drying surface of the drum a layer of disodium

phosphate liquor containing, by weight of said liquor, monosodium phosphate in amount not more than 0.02% and trisodium phosphate in amount not more than 0.05%, on a 50° Bé. at 5 212° F. basis, heating said layer to convert the same to an at least partially dried crust, forming on such crust a layer of said disodium phosphate liquor, and continuing heating of the disodium phosphate material on the drum drying surface to thereby form substantially dry material readily removable from said surface.

4. In the process for drying disodium phosphate liquor by procedure involving use of a drum drier, the steps comprising forming on the drying surface of the drum a layer of disodium phosphate liquor of concentration of 49-51° Bé. at temperature of 200-220° F. and containing, by weight of said liquor, monosodium phosphate in amount not more than 0.02% and trisodium phosphate in amount not more than 0.05%, on a 50° Bé. at 212° F. basis, heating said layer to convert the same to an at least partially dried crust, forming on such crust a layer of said disodium phosphate liquor, and continuing heating of the disodium phosphate material on the drum drying surface to thereby form substantially dry material readily removable from said surface.

5. In the process for drying disodium phosphate liquor on a heated drying surface, the steps comprising forming on said surface a relatively thin layer of disodium phosphate liquor, heating said layer to convert the same to an at least partially dried crust, forming on such crust a relatively thin layer of disodium phosphate liquor, and continuing heating of the disodium phosphate material on said drying surface to thereby form substantially dry material readily removable therefrom.

6. In the process for drying disodium phosphate liquor on a heated drying surface, the steps comprising forming on said surface a relatively thin layer of disodium phosphate liquor of concentration of not less than 49° Bé. at temperature of 200-220° F., heating said layer to convert the same to an at least partially dried crust, forming on such crust a relatively thin layer of said disodium phosphate liquor, and continuing heating of the disodium phosphate material on said drying surface to thereby form substantially dry material readily removable therefrom.

WILLIAM B. TOWNER.
